Primary Examiner — Darlington Ly*Assistant Examiner* — Giang Hoang Tran(57) **CLAIM**

The ornamental design for an electric snow scooter as shown and described.

DESCRIPTION

FIG. 1 is a top, rear and right side perspective view of an electric snow scooter showing my new design;

FIG. 2 is a bottom, front and left side perspective view thereof;

FIG. 3 is a top, front and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 1;

FIG. 12 is an enlarged view of portion 12 in FIG. 1;

FIG. 13 is an enlarged view of portion 13 in FIG. 2;

FIG. 14 is an enlarged view of portion 14 in FIG. 2; and,

FIG. 15 is an enlarged view of portion 15 in FIG. 5.

The broken lines in the drawings illustrate portions of the electric snow scooter which form no part of the claimed design.

The dot dashed broken lines in FIGS. 1, 2, 5, and 10-15 indicate the boundaries of the enlarged views and are used for annotative purpose only. They do not limit or define the scope of the claimed design.
